APPARATUS FOR MAKING DISINTEGRATING TOP SHOT WADS

William N. King and Nicholas A. Romanchuk,
Anoka, and Ralph Lynn, Minneapolis, Minn.,
assignors to Federal Cartridge Corporation,
Minneapolis, Minn., a corporation of Minnesota

Application December 6, 1948, Serial No. 63,746

4 Claims. (Cl. 91—55)

1

This invention relates to an apparatus for making disintegrating top shot wads of the type disclosed and claimed in the copending application of Harold C. Russell, Serial No. 609,238, filed August 6, 1945, and made by the process disclosed and claimed in the copending application of Harold C. Russell and William N. King, entitled "Process of Making Disintegrating Top Shot Wads," filed of even date herewith.

The common shot shell cartridge made prior to said Russell application consisted of a shell component made of a rolled paper tube closed at one end by a thin metal cup, usually of brass, which was shaped to provide the ejector flange and served to hold the central primer cap. In the common sequence of shotgun shell (shot shell) loading, powder is first introduced into the tube-cup component and covered by a thick "powder wad" of hair felt or flexible cork composition, such as described in Patent No. 1,485,337. Above the powder wad there is placed the shot loading of pellets which are in turn held in place by a thin "top shot wad" of paper board, the latter being held in place by a roll-crimp in the end of the paper tube.

Shot shells of this type are subject to the disadvantages because the top shot wad in at least a certain percentage of the shells tends to impede the shot when fired, and cause mal-distribution of the shot pellets. The thick powder wad causes no trouble because it is below the shot load in the shell and trails behind the shot (known as the "shot string") when the shell is fired. For many years it was known that when fired, some shot shells produced what is known as a "blown pattern" wherein large areas within the usual pattern circle would receive few or no shot pellets. The fact that the top shot wad caused this unsatisfactory performance was not known and bad performance was accepted because, up to the time of said Russell invention of application Serial No. 609,238, better performance could not be obtained in any known shot shell construction having a top shot wad. This was the reason for the development of the so-called "wadless crimp" shot shells which give a satisfactory pattern at the expense of lesser loading space within the shell interior and hence at the expense of lower fire power.

After extensive research both in the laboratory and in the field, including actual photographing of many shot charges as fired, the aforesaid Harold C. Russell discovered that the "blown pattern" phenomena was due to the fact that when the shell was fired the top shot wad

2

remained intact or nearly so in a large percentage of shells and was projected along in front of the "shot-string" during the early part of the trajectory of the charge and the top shot wad thereby caused poor distribution of the pellets. This difficulty in shot shell performance was solved by the invention of the disintegrating top shot wads described and claimed in the aforesaid application Serial No. 609,238.

10 The present invention is a result of continued research on the subject and is directed to apparatus for commercial production of disintegrating top shot wads of the aforesaid improved shot shells containing such disintegrating wads.

15 It is an object of this invention to provide improved apparatus for manufacturing disintegrating top shot wads by a continuous process and to provide apparatus wherein such manufacture may be carried out with great speed and at low 20 cost and wherein the disintegrating top shot wads are produced with great uniformity in respect to the qualities of size, density and frangibility.

It is also an object of the invention to provide an improved apparatus for making top shot wads 25 under controlled conditions.

It is a further object of the invention to provide an apparatus for making resin-impregnated top shot wads of level character, completely dry, polymerized and hard to cut to shape.

30 Other and further objects of the invention are those inherent in the apparatus herein illustrated described and claimed.

The invention is illustrated with reference to the drawings in which corresponding numerals 35 refer to the same parts and in which

Figure 1 is a side elevational view from the left side of the entire apparatus;

40 Figure 2 is a partial side elevational view, partly in section and partly broken away, taken from the opposite side (viz. the right side) as compared with Figure 1 and showing a portion of the apparatus shown in Figure 1;

Figure 3 is a plan view of the portion of the apparatus shown in Figure 2;

45 Figure 4 is an enlarged partial side elevational view from the right side, partly in section, showing the impregnating section of the apparatus of Figures 1, 2 and 3;

50 Figure 5 is a plan view of that portion of the apparatus shown in Figure 4;

Figure 6 is a side elevational view of the wad-cutting portion of the apparatus shown in Figure 1, except from the right side thereof.

55 Referring to the drawings and particularly to

Figure 1 thereof, the apparatus in overall aspect includes the following components:

At the left in Figure 1 there is shown an impregnating tank section, shown under the bracket 10. Adjacent the impregnating section there is illustrated a drying and polymerizing section 11 and adjacent thereto is a catalyzing section 12. At the right end of Figure 1 there is shown the wad-cutting apparatus 13.

The impregnating section 10 consists of a tank generally designated 15 which is supported on an angle iron frame 16. The tank is closed at the bottom and sides but is open at the top. The tank is, therefore, accessible only from the top and in it there is placed a framework generally designated 14, consisting of angle iron posts 17, 18, 19, 20 at the four corners thereof. The angle iron posts 17-20 are fastened at the bottom to a rectangular stabilizing frame 21 and they are fastened together at the top by angle iron side frame members 22 and 23, the side frame members being fastened together sturdily by the cross frame members 24 and 25. The bottom frame members 21 and the top frame members 22, 23, 24 and 25 are positioned on the outside of the corner angles 17-20 and consequently the corner angles provide a vertical guide defined by the angles at the corners. From side frame members 22 and 23 at the top of the frame 14, there are provided inwardly extending lugs 28, 29, 30 and 31. The top lugs 28, 29, 30 and 31 serve as slides in which four rods 32, 33, 34 and 35 are adapted to move upwardly and downwardly. The four rods have a length such that they extend from the bottom of the frame 14 to slightly above the top of the frame, as shown in Figure 4. At the bottom ends of the rods 32-35 there is attached a rectangular frame 36 which has a dimension such that it slides easily within the space provided by the vertical corner angles 17-20 at the four corners of the frame 14. The tops of the rods 32-35 are attached together by a rectangular frame consisting of cross frame members 37, 38 and 41 and side frame members 39 and 40. A hook 42 is provided at the center of member 41 and when it is lifted, the entire assembly consisting of frame pieces 37-41 and the rods 32-35 and the rectangular frame 36 attached to the lower ends of the rods are all simultaneously lifted. Since the frame 36 slides within the four corner angles 17-20 of the frame 14, the lower frame member 36 is stabilized against sideways.

Adjacent the lower ends of rods 34 and 35 are mounted two rollers 44 and 45, the bearings being mounted by means of blocks 46 and 47 attached to the vertical rods. The rollers rotate on the shafts 48 and 49 mounted on the blocks. Accordingly, when the framework composed of the rods 32-35 etc. is lifted, the rollers 44 and 45 are likewise lifted from the full line position of Figure 4 to the dotted line position.

In the dotted line position the rollers 44 and 45 are slightly above the central roller 50 which is mounted for rotation on a shaft 51 that is supported in blocks 52, the latter being supported on angle iron side frame members 53 at each side of the main frame 14. When the lower rollers 44 and 45 have been raised to the position shown in dotted lines of Figure 4, the paper board strip (web) can easily be threaded under the roller 44, thence over the roller 50 and thence under the roller 45. By holding the paper over roller 50 and then lowering the rollers 44 and 45 by means of the hook 42 additional paper board

strip is then drawn down to the position shown in full lines in Figure 4.

Upon the side frame members 22 and 23 there is also mounted a roller 54 which is supported on bearing blocks 55 that are in turn mounted on the overhanging ends of the angles 22 and 23. The roller 54 serves to guide the incoming strip of paperboard before it enters the tank 15 for treatment. Another roller 58 of somewhat larger diameter rotatably supported on the shaft 59 and bearing block 60 of the drying section 11, as also shown in Figure 4. The roller 58 serves to guide the web of impregnated paper board stock out of the impregnating tank 15 and thence into the drying and polymerizing section 11.

Upon the framework 14 there is also mounted a heating coil which enters by pipe 61 which extends to the lower part of the tank 15 and thence extends upwardly through a plurality of turns 62 and finally emerges from the tank by way of pipe 63. The heating coil is suitably attached to the angle iron framework 14.

The entire tank 15 and framework 14 and all mechanisms and pipes and rods thereon are composed of stainless steel. It will be evident that the tank 15 merely rests upon the angle iron frame 16 and that when the framework 14 is lifted out of the tank, all mechanisms are accordingly removed from the tank. This greatly facilitates cleaning of the tank for it is simply necessary to disconnect the heating pipes and then move the lower framework 16 away from other components of the machine, whereupon the frame 14 can be lifted out and cleaned separately from the tank 15.

Referring to Figures 1 and 2, particularly, the drying and polymerizing section of the apparatus, shown under the bracket 11, is composed of a box generally designated 65 having end walls 66, 67, side walls 68, 69 and top 70 and bottom 71. The box is supported on a leg frame 72 and is wholly closed except for the following apertures thereinto: In the end wall 66 there is an aperture 73 through which the impregnated sheet enters the box 65. In the end wall 67 there are apertures 74 and 75 and 76 through which the web passes out of and then returns into the drying and polymerizing section 11 during certain parts of its travel. Into the side walls 68 of the box of the drier there are three hot air inlets 78, 79 and 80 and an outlet 81. Upon the top of the drier there is an exhaust blower 82 having an exhaust outlet 83 to the exterior of the building in which the machine is housed.

Supported upon the side walls of the drying section are a plurality of roll shafts 84, 85 and 86 which support the rollers 88, 89 and 90, respectively, these rollers defining the path of travel of the impregnated web W through the drying and polymerizing section 11 of this portion of the apparatus. Thus, the web W after passing over the roller 58, which is supported upon frame 87 on the exterior of the end wall 66, passes through the slit 73 and thence travels through the space 91 which is defined by the top 70 of the drying section and an interior baffle 92 which extends from the side walls 68 to a position closely adjacent roller 88. The web W, after passing through this space 91 in the direction of arrow 93, passes over the roller 88 and thence returns in the space 94 moving in the direction of the arrow 95. The space 94 is defined by the baffle 92 and a baffle 96 which extends from the end wall 67 to a position closely adjacent the roller 89. The web W, after passing through the

space 94, traverses roller 89 and returns through the space 98 moving in the direction of arrow 99 until it passes out of the slit 74 and between a continuation of that slit formed by the spaced plates 100 and 117. After passing between the plates 100 and 117 the web W has reached the catalyzing section shown under the bracket 12 and in this section of the apparatus, which is defined by the framework 101, 102, 103, 104 and the leg frame 105, the web reaches and passes around a roller 106 which is supported on shaft 107, the latter in turn being mounted upon the bearing bracket 108 that is fastened to the frame member 103. The web W then passes between rollers 110 and 111 which are of felt or other absorbent material. The roller 111 is situated in a tank 112 which has an overflow at 113 and a drain at 114. An inlet pipe 115 is situated above the roller 110 and during operation a solution of acidic material, such as a 5-10% solution of phosphoric acid, is continuously run through pipe 115 from whence it drains upon the upper roller 110 and thence onto the web and over it and into the tank 112 where the lower roller 111, being partially submerged is continuously wetted by the acidic solution. The level in the tank 112 is defined by the overflow 113, from which any excess is again pumped back through pipe 115. The web W may be guided by the roller 116 before entering the catalyzing tank 112 where the aqueous solution of acidic material is applied to both sides of the web. The web then re-enters the drying section 11 through the slit 75 whence it continues through the space 118 which is defined by a baffle 119 extending from the wall 66 to a position closely adjacent the wall 67. The space 118 is defined at its lower portion by a baffle 120 which extends from the wall 67 to a position closely adjacent the roller 90. The web W moving in the direction of arrow 121 in space 118 thence passes around roller 90 and into the space 123 where it moves in the direction of arrow 124 until it reaches the wall 67 where it passes out of the slit 67 and after passing through the lower portion of the catalyzing section 12, it enters the wad-cutting section 13.

A heater, not shown, is provided for introducing air having a temperature of 300-400° F. through the opening 80 whence the air passes in the direction of arrows 125 and 126 into the space 94 where the heated air travels again, counter-clockwise to the movement of the web, in the direction of arrows 127 and 128 and enters the inlet of the suction blower 82. In the left-hand end of section 98 there may be a localized positive pressure during operation of the apparatus, but no considerable amount of heated air leaves the slit 74 because of the extension plates 100 and 117 which, as an extension of the slit, form sufficient local interference to prevent all but a small amount of heated air from escaping. A second heater not illustrated or a portion of the first heater, capable of producing air heated to a temperature of 400-550° F. is introduced through inlet 78, whence the heated air moves in the direction of arrows 129 and 130 to the space 118 where it continues and with additional 400-500° F. air introduced through inlet 79 via arrow 131 passes around the end of baffle 119 as shown by arrow 131 and joins that entering at inlet 80. It will be noted that baffle 92 terminates a short distance from roller 88 and that baffles 96 and 120 terminate short distances from rollers 89 and 90, respectively. Thus, space is provided adjacent the rollers for the free passage of heated air from

one section to another where the web makes a path over the roller.

Referring to Figures 1 and 6 particularly there is illustrated a vertically acting punch mechanism which is arranged to move the flat, hard, impregnated and polymerized web W in a horizontal path over punching dies and, while being so moved, to punch from the web discs of the web which serve as the top shot wads. For accomplishing this purpose the press includes a press frame 134 upon which are mounted a pair of entering feed rolls 135-136 and a pair of leaving feed rolls 137-138. It may be noted that in Figure 1 the movement of the web is from left to right, but in Figure 6 the detail view is there shown from the opposite side of the machine, as compared with Figure 1, and in Figure 6 the web movement is from right to left, as indicated by the arrow 139. Upon the frame 134 there is also mounted a die plate 140 which supports the cutting dies 150, these dies being supported upon a plurality of springs 151. Beneath the die plate is a receptacle 152 for receiving the wads as punched by the machine. Upon the punch press there is also mounted a vertically reciprocating head 153 carrying a plurality of punch units 154 and 155 which are aligned with the corresponding openings of the die plate and the head 153 is arranged to be oscillated up and down in the direction of the double arrow 156. The reciprocation of the head 153 thus punches out a plurality of top shot wads from the disc for each motion of the head up and down.

Through apparatus not illustrated the feed rolls 135-136 and 137-138 are geared to the movement of the reciprocating head 153 in such a way that the feed rolls rotate a short distance after the punches 154-155 have moved upwardly from the web and the feed rolls thus advance the web step-by-step as the head reciprocates. Referring to Figure 1 it will be noted that the feed rolls 136 and 138 are geared together by means of the gearing 160 and that the gear 160 is provided with a coaxially mounted sprocket 161 of the chain drive 162. The chain 162 runs over sprocket 163 mounted upon the side wall of the drying and polymerizing section cabinet. Coaxially mounted with sprocket 163 is a smaller sprocket 164 over which runs the chain 165 which is tracked over the drive sprockets 166 of roller 89, the drive sprocket 168 of roller 58 drives an idler drive sprocket 169 which is mounted so that slack in the chain may be taken up, the sprocket 170 of roller 90 and the sprocket 171 of roller 88. In this manner as the punch press at the punching section 13 reciprocates and accordingly moves the feed rolls of the punch press, the chain 162 is correspondingly moved and it, through the chain 165, drives a sufficient number of rollers in the drying section and impregnating section so as to advance the web through those sections in preparation for final delivery to the punching section. The various sprockets at 161 and 163, and the size of sprockets 164, 166, 168, 169, 170, 171 are proportioned so that the web is fed into the impregnating section and through the drying, polymerizing and catalyzing section and is delivered to the wad cutting section 13 at a rate just sufficient to fulfill the feeding requirements for wad cutting.

The rate of feed for acceptable commercial practice is approximately 14 lineal feet per minute, although a lesser or greater speed may be utilized if desired.

As many apparently widely different embodi-

ments of this invention may be made without departing from the spirit and scope thereof, it is to be understood that we do not limit ourselves to the specific embodiments herein.

What we claim is:

1. An apparatus for preparing dried, polymerized, resin-impregnated paper board in preparation for punching disintegrating top shot wads therefrom comprising means for impregnating a continuous web of paper board with resin and for then drying and polymerizing the same, said means for impregnating including a dip tank open at the top, a supporting frame removably positioned in said dip tank, means on said frame for guiding the web downwardly into the tank in a plurality of passes and upwardly from said tank, said supporting frame having a base and uprights disposed within said tank and being entirely removable as a unit through the open top of the tank and a surrounding heating coil mounted on the framework within the tank, said heating coil being removable thru the open top of the tank in conjunction with the frame on which said coil is mounted.

2. An apparatus for making disintegrating top shot wads comprising means for impregnating a web of paper, including a heated dip tank for resin solution open at the top, roll means for guiding the web therethrough, said roll means comprising an introductory roll adapted to receive said web of paper at normal room temperature and an intermediate roll, said intermediate roll being situated parallel to said introductory roll and slightly below the same, a pair of lower rolls mounted upon a vertically moveable frame, said pair of rolls being freely moveable from the position well below the intermediate roll to a position slightly above the intermediate roll for threading of said web therethrough, said roll means being operative to guide said web through said dip tank in a plurality of passes, heated coil means situated within said tank, said roll means and said heated coil means mounted upon a frame which is readily removable through the top of said tank, means for raising and lowering said frame relative to the tank, a drying chamber having side walls, end walls, and top walls, said chamber having a plurality of parallel baffles therein, said baffles alternately attached to opposite ends of said chamber for defining a course of substantially parallel paths of travel for said web through said chamber, rollers in said chamber for guiding said web through said path, means for introducing heated air at a moderate temperature, intermediate the course of travel through said paths and for withdrawing said air therefrom adjacent the beginning of said paths, and means for introducing more intensely heated air adjacent the end of said path so as to form a moderately heated horizontal temperature zone at the upper portion of said chamber and a more intensely heated horizontal temperature zone at the lower portion thereof, means for withdrawing said web from said drying chamber subsequent to its travel through said moderate temperature zone and before its travel through said more intensely heated temperature zone, means for substantially preventing the escape of heated air through said means for withdrawing said web, impregnating roll means for impregnating said web with a liquid while said web is so withdrawn, means for then introducing said impregnated web into the more intensely heated temperature zone, means for then withdrawing said web in a flat condition from said intensely

heated chamber and for moving it directly without bending to means for punching discs from the web, said means for punching comprising a reciprocating punch and feed rolls thereon operated for step-by-step rotation in synchronism with the reciprocation of said punch means for advancing the web as it is punched, gear means connecting the feed rolls of the punch means and remaining sections of the apparatus for feeding the web therethrough preparatory to punching, said punch feed rolls rotating in synchronism with the said roll means for feeding and guiding said web through said chamber, whereby the sheet is punched while it is level and flat directly as it is produced to prevent bending and fracture of the web incident to handling.

3. In an apparatus for making disintegrating top shot wads, means for impregnating a web of paper, including a heated dip tank open at the top for resin solution, roll means for guiding the web therethrough, said roll means comprising an introductory roll adapted to receive said web of paper at normal room temperature and an intermediate roll, said intermediate roll being situated parallel to said introductory roll and slightly before the same, a pair of lower rolls mounted upon a vertically moveable frame, said frame being vertically movable relative to said tank and means for so moving said frame, said pair of rolls being thereby freely moveable from the position well below the intermediate roll to a position slightly above the intermediate roll for threading of said web therethrough, said roll means being operative to guide said web through said dip tank in a plurality of passes, heated coil means situated within said tank, said roll means and said heated coil means mounted upon a frame which is readily removable through the top of said tank.

4. In an apparatus for making disintegrating top shot wads a drying chamber having side walls, end walls and top walls, said chamber having a plurality of parallel baffles therein, said baffles alternately attached to opposite ends of said chamber for defining a course of substantially parallel paths of travel for said web through said chamber, rollers in said chamber for guiding said web through said path, means for introducing heated air at a moderate temperature intermediate the course of travel through said paths and for withdrawing said air therefrom adjacent the beginning of said paths, means for introducing more intensely heated air adjacent the end of said path so as to form a moderately heated horizontal temperature zone at the upper portion of said chamber and a more intensely heated horizontal temperature zone at the lower portion thereof, means for withdrawing said web from said drying chamber subsequent to its travel through said moderate temperature zone and before its travel through said more intensely heated temperature zone, impregnating roll means for impregnating said web with a liquid while said web is so withdrawn, means for then introducing said impregnated web into the more intensely heated temperature zone and means for then withdrawing said web from said drying chamber and means for punching discs from the web as it leaves the drying chamber comprising a reciprocated punch and feed rolls thereon with means operating said rolls in step-by-step rotation in synchronism with the reciprocation of said punch means, for advancing the web as it is punched, gear means connecting the punch means feed rolls and said means for introducing and

withdrawing said web from said chamber for feeding the web from said chamber in flat condition preparatory to punching and for operating said punch feed rolls in synchronism with said means for introducing and withdrawing said web from said chamber to punch said web at the completion of the drying operation thereby preventing bending and fracture of the web.
